(57) CLAIM

The ornamental design for a scarf with fastening devices, as shown and described.

DESCRIPTION

FIG. 1 is a perspective view of a scarf with fastening devices in a wrapped position;

FIG. 2 is a top plan view of the scarf with fastening devices in a flat position;

FIG. 3 is a bottom plan view thereof;

FIG. 4 is a front elevational view thereof, the rear elevational view being a mirror image of the front view; and,

FIG. 5 is a left side elevational view, the right side elevational view being a mirror image of the left side view.
